US00D626877S

(12) United States Design Patent
Castaline et al.

(10) Patent No.: US D626,877 S
(45) Date of Patent:  Nov. 9, 2010

(54) DOUBLE LEAF JEWELRY BAIL

(76) Inventors: Jeffrey J. Castaline, 41 S. Railroad Ave., San Mateo, CA (US) 94401; Hiroyuki Kobayashi, 41 S. Railroad Ave., San Mateo, CA (US) 94401

() Term: 14 Years

(21) Appl. No.: 29/362,205

(22) Filed: May 21, 2010

(51) LOC (9) Cl. 11-02

(52) U.S. Cl. D11/67

(58) Field of Classification Search D11/1-2, D11/40-41, 43-50, 53, 56, 60, 63, 65, 67, D11/75-78.1, 86, 89, 85-105, 108-109, 115-116; 63/1.12, 1.13, 1.14, 1.16, 1.18, 13, 14.1, 63/35, 38, 39
